Inventor

George R. Bassett,

UNITED STATES PATENT OFFICE.

GEORGE R. BAEUMEL, OF GREAT BEND, KANSAS.

ADJUSTMENT FOR BINDER REELS.

Application filed December 7, 1922. Serial No. 605,506.

To all whom it may concern:

Be it known that I, GEORGE R. BAEUMEL, a citizen of the United States, residing at Great Bend, in the county of Barton and State of Kansas, have invented certain new and useful Improvements in an Adjustment for Binder Reels, of which the following is a specification.

This invention relates to an adjustable binder reel, and more especially to those adapted for cutting corn and like cereals, and the prime object of the invention is to improve the construction of the mechanism for permitting the vertical adjustment of the binder reel.

A further object of the invention is to provide a vertical adjustable binder reel, so that same can be operated by one man from either side of the binder.

A still further object of the invention is to provide an adjustable binder reel of the above indicated character, which is simple in construction and operation, durable, efficient for the purpose intended, and one that can be manufactured and placed on the market for sale at a relatively low cost.

These and like objects of the invention will be better understood as the description follows and as is specifically pointed out in the appended claims.

Referring to the accompanying drawings which form a part of this specification and which clearly illustrate the construction and operation of my improved harvester,

Figure 1 is an end elevation of a harvester showing my improved adjustable reel applied thereto.

Figure 2 is a side elevation of my improved adjustable binder reel.

Figure 3 is a side elevation of the binder reel operating mechanism, showing same detached from the harvester and broken in two.

Figure 4 is a horizontal section taken on line 4—4 of Figure 3, and

Figure 5 is an enlarged fragmentary side elevation of a part of the binder reel operating mechanism, taken from the reverse side shown in Figure 3.

Referring to the accompanying drawings in detail, like characters will be used to designate like parts in the different views.

In the drawings, the numeral 1 indicates the platform of a binder, which is mounted on ground wheels 2. As my invention re-

lates particularly to means for elevating the binder reel to various heights according to the height of the grain, cereal, or the like, I have for the purpose of better illustrating my invention eliminated other parts of the harvester from the drawings.

Mounted on the platform 1 at opposite corners are a pair of standards 3, each of which is provided with a slot 4 therein, running its entire length. Each of the standards 3 have a plate 5 formed thereon, which is positioned on the opposing faces of the standards and are of equal length. One side of each of the plates 5 has a rack bar 6 thereon. A band which is approximately U-shaped, said band being indicated by the numeral 7, is positioned around each of the standards 3 and plates 5 and are fastened together by means of bolts 8 at their ends. A shaft 9 is journaled in each of the U-shaped bands 7, said shaft being adapted to pass through the slot 4 in the standard, as is clearly shown in Figure 2. A gear 10 is keyed on the shaft 9 and adapted to engage the rack bar on the plate 5. A gear 11 is keyed on the extreme end of the shaft 9 and is adapted to mesh with a gear 12 rotatably mounted on one side of the U-shaped band 7. The gear 12 is provided with a handle 13, whereby rotation may be imparted to the gear 10 through the gear 11 and shaft 9. An ear 14 is formed on each of the bands 7, and a shaft 15 is positioned between said ears being pivotally mounted therein, said shaft having a reel 16 mounted therebetween. At one end of said shaft 15 is secured a gear 16^a meshing with a gear 16^b carried on a vertical shaft 16^c. Said shaft 16^c is adapted to be moved vertically with the bands 7 being slidably received in a sleeve 16^d, yet keyed thereto for rotation therewith. The sleeve 16^d is rotated by a pair of bevel gears 16^e, one of which is mounted on a horizontal shaft 16^f driven from the mechanism of the harvester. It can thus be seen that when the reel 16 is raised or lowered the shaft 16^c will slide within the sleeve 16^d and always form a driving connection for rotating the reel 16.

In using a harvester in a field, it is a very difficult matter to bring the binder reel into engagement with the grain, if the grain is leaning over or if the harvester is traveling over uneven ground. With the

use of my improved attachment for harvester, this trouble is entirely eliminated as the binder reel can be adjusted to various heights from either side of the machine, 5 by the operator working the handle 13 of the gear 12. The binder reel is held in any adjusted position by means of a pin 17, that passes through openings 18 in the gear 12 and through an opening 19 formed 10 in the disk 20 carried by the band 7.

In view of the foregoing description of my invention taken in connection with the accompanying drawings, it is thought that any further explanation as to the construction, operation, and objects of the invention 15 is unnecessary.

While I have shown and described the preferred form of my invention, I realize that various minor changes may be resorted 20 to, without departing from the spirit and scope of the invention as claimed, and therefore, I do not wish to limit myself to the exact details of construction shown, nor to the combination and arrangement of 25 parts.

What I claim as new and desire to secure by Letters Patent is:

1. A device of the character described, comprising a platform, a pair of standards 30 mounted on said platform, each of said standards provided with a longitudinal slot therein, a rack bar formed on each of said standards, a band arranged about and slide- 35 able on each of said standards, a shaft mounted in each of said bands and extending through the slots in the respective standards, a gear mounted on each shaft and meshing with each rack bar, gears ar- 40 ranged upon the opposite ends of each of said shafts for rotating the same to ele- vate said bands, and a reel suspended be- 45 tween said standards and supported by said bands adapted to be elevated therewith.

2. A device of the character described, comprising a platform, a pair of standards 45 mounted on said platform each of which being provided with a longitudinal slot therein, a rack bar formed on each of said standards, a band about said standards and slidably mounted thereon, a reel supported 50 between said standards and carried by said bands, a shaft mounted in each of said bands and each extending through the re- spective slot in each of said standards, a gear mounted on each of said shafts mesh- 55 ing with each of said rack bars, gears ar- ranged at the opposite ends of each of said shafts for rotating the same, one of said last mentioned gears having openings provided therein, and pins adapted to be 60 received in each of said bands extending through said openings in said gears for locking said gears against rotary movement.

3. A device of the character described, comprising a platform, a pair of standards 65 mounted on said platform, each of said standards being L-shaped in cross section and provided with a longitudinal slot in one of their sides, a rack bar formed on the other side of each of said standards, 70 a band slideable on each of said standards, a shaft mounted in each of said bands ex- tending through each of said slots in each of said standards, a gear mounted on each 75 of said shafts meshing with each of said rack bars, means for rotating each of said shafts for elevating said bands, and a reel having its ends pivotally supported in each of said bands.

In testimony whereof, I have affixed my 80 signature in the presence of two witnesses.

GEORGE R. BAEUMEL.
